UNITED STATES PATENT OFFICE

164,762

FLUID PUMP

Jeremiah J. Colbert, St. Joseph, Mo.

Application July 21, 1949, Serial No. 4,056

Term of patent 14 years

(Cl. D65—1)

To all whom it may concern:

Be it known that I, Jeremiah J. Colbert, a citizen of the United States, residing at St. Joseph, in the county of Buchanan and State of Missouri, have invented a new, original, and ornamental Design for a Fluid Pump, of which the following is a specification, reference being had to the accompanying drawing, forming a part thereof.

Fig. 1 is a side elevational view of a fluid pump, showing my new design.

Fig. 2 is a top plan view thereof.

Fig. 3 is a front end elevational view thereof; and

Fig. 4 is a rear end elevational view thereof.

I claim:

The ornamental design for a fluid pump, as shown.

JEREMIAH J. COLBERT.
